A. MCPHERSON

HOG SPRAYER

Filed Jan. 16, 1924

INVENTOR.

A. McPherson

BY
Watson E. Coleman
ATTORNEY.

UNITED STATES PATENT OFFICE.

ANDREW MCPHERSON, OF WARD, SOUTH DAKOTA.

HOG SPRAYER.

Application filed January 16, 1924. Serial No. 686,594.

To all whom it may concern:

Be it known that I, ANDREW MCPHERSON, a citizen of the United States, residing at Ward, in the county of Moody and State of South Dakota, have invented certain new and useful Improvements in Hog Sprayers, of which the following is a specification, reference being had to the accompanying drawings.

This invention relates to certain improvements in hog sprayers and it is an object of the invention to provide a mechanism operating automatically to spray or sprinkle a liquid insecticide or other medicated or antiseptic liquid over hogs or other stock.

Another object of the invention is to provide a novel and improved device of this general character comprising a container adapted to hold a supply of desired liquid under pressure together with a spraying medium in communication with said container, said medium being normally inactive but operating under the influence of the hog or other stock passing under the spraying medium.

The invention consists in the details of construction and in the combination and arrangement of the several parts of my improved hog sprayer whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in end elevation of a hog sprayer constructed in accordance with an embodiment of my invention;

Figure 2 is a sectional view taken substantially on the line 2—2 of Figure 1;

Figure 3 is an enlarged fragmentary sectional view taken through a spraying element as herein disclosed;

Figure 4 is a fragmentary view in perspective illustrating a connection of a rod with a platform or trip board.

As disclosed in the accompanying drawings, 1 denotes a pair of sills arranged in parallelism and the opposite end portions 55 of said sills have secured thereto the up-

standing supporting frames 2 each being herein disclosed as substantially in the form of an inverted U. The upper portion of each of the frames 2 have the side members thereof connected by a saddle 3 providing a support for the tank or container T. Disposed over the tank or container T and secured to the opposite end portions of the saddle 3 is a clamping rod or member 4.

As herein disclosed, the tank T is cylindrical in form and is provided in its upper portion with a normally closed filling opening 5.

Arranged exteriorly of the tank or container T and supported thereby is a hand pump 6 operating to provide the tank or container T with a charge of compressed air to facilitate the discharge of the liquid therein through the spraying elements E to be hereinafter referred to. The pump 6 has leading from the discharge opening thereof a pipe 7 which extends within the tank or container T and terminates in close proximity to the bottom thereof whereby the liquid within the tank or container T serves to seal to prevent escape of the compressed air within the tank or container T.

The sills 1 at a point substantially midway between the frames 2 are provided with the upstanding plates 8 which serve as supports for the pivot members 9 of the oppositely disposed platforms or trip boards 10. The boards or platforms 10 have swinging movement in a vertical direction and are normally in a raised or substantially horizontal position. When in their normal position the platforms or boards 10 are substantially coplanar with the steps 11 supported by the sills 1 outwardly of the frames 2, the rear marginal portions of the steps 11 being provided with the inwardly directed flanges 12 with which the outer extremities of the platforms or boards 10 contact from below whereby the upward swinging movement of the boards or platforms 10 is positively limited.

A spraying element E is arranged adjacent to each end of the tank or container T and comprises a nozzle 14 disposed exteriorly of the tank or container with the lower portion of the nozzle substantially flush with the lower portion of the tank or container T so that said nozzle is protected against contact therewith by an animal passing under the tank or container. The

nozzle 14 is in communication with the interior of the tank or container T through the pipe or conduit 15.

Flow through the nozzle 14 is under control of a valve 16 operatively engaged with a rock arm 17 supported by an outstanding bracket 17' carried by a saddle 3. The rock arm 17 is also operatively engaged with a trip rod 18, said rod extending downwardly adjacent to a side member of a frame 2 and having its lower end portion operatively engaged, as at 19, with the outer end portion of the platform or trip board 10, so that upon depression of such platform or board 10 the valve 16 will be adjusted into open position so that the contents of the container or tank T will be sprayed or sprinkled upon an animal passing under such tank or container. The valve 16 is normally maintained closed through the instrumentality of a retractile member 20, herein disclosed as a coil spring, having one end portion secured to the rod 18 and its opposite end portion to a side member of a frame 2. The side members of the frames 2 are each provided with a series of longitudinally spaced openings 21 to provide means whereby the saddles 3 can be raised or lowered to compensate for animals of different sizes.

Secured to the lower portions of the vertical members of the frames 2 connected to similar sills 1 are the plates or guards 22 which serve to maintain the animals upon the platforms or boards 10 when passing under the tank or container T.

By having the elements E positioned at opposite ends of the tank or container T and outwardly thereof it is assured that the liquid will be sprayed or evenly distributed over the stock from head to tail.

From the foregoing description it is thought to be obvious that a hog sprayer constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A spraying mechanism comprising, in combination, a pair of sills arranged substantially in parallelism, a tank supported by and above said sills, transversely disposed steps carried by the opposite end portions of the sills, platforms extending transversely of the sills and positioned between the steps, means for pivotally sup-

porting the inner marginal portions of the platforms to permit said platforms to have swinging movement in a vertical direction, said platforms and steps being normally substantially coplanar, said steps being provided with means with which the platforms contact from below to limit the upward swinging movement of the platforms, spraying elements arranged at opposite ends of the tank and in communication therewith, a valve for controlling the flow through each of the elements, an operative connection between each of the platforms and a valve for moving said valve into open position upon depression of the platform, means coacting with each of said operative connections for constantly urging upwardly the platform with which such connection is engaged, and upstanding guard plates arranged above and at opposite sides of the platforms and below the tank.

2. A spraying mechanism comprising, in combination, a pair of sills arranged substantially in parallelism, a tank supported by and above said sills, transversely disposed steps carried by the opposite end portions of the sills, platforms extending transversely of the sills and positioned between the steps, means for pivotally supporting the inner marginal portions of the platforms to permit said platforms to have swinging movement in a vertical direction, said platforms and steps being normally substantially coplanar, said steps being provided with means with which the platforms contact from below to limit the upward swinging movement of the platforms, spraying elements arranged at opposite ends of the tank and in communication therewith, a valve for controlling the flow through each of the elements, a rock shaft operatively engaged with a valve for moving the valve into open position upon rotation of the rock shaft in one direction, a rod operatively engaged with the rock shaft and with a platform, depression of said platform rocking the shaft in a direction to move the valve into open position, a retractile member engageable with the rod to constantly urge said platform in the opposite direction and to maintain the same in its normal position and upstanding guard plates arranged above and at opposite sides of the platforms and below the tank.

3. A spraying mechanism comprising, in combination, a pair of substantially parallel sills, upstanding supporting frames secured to said sills, each of said frames being substantially in the form of an inverted U, a saddle bridging the space between the upper portions of the side members of each of the frames, means for connecting the saddles to the side members, a tank resting on the saddles, means for holding the tank to the saddles, a spraying element in communica-

tion with the tank, and means operable under weight for opening communication between the element and the tank.

4. A spraying mechanism comprising, in combination, a pair of substantially parallel sills, upstanding supporting frames secured to said sills, each of said frames being substantially in the form of an inverted U, a saddle bridging the space between the upper portions of the side members of each of the frames, means for connecting the saddles to the side members, a tank resting on the saddles, means for holding the tank to the saddles, a spraying element in communication with the tank, a nozzle in communication with the tank, a valve for controlling the flow through the nozzle, an outstanding bracket carried by a saddle, a rocking arm pivotally engaged with said bracket and operatively engaged with the valve for moving the valve, and means operable under weight connected with each rock arm for swinging the rock arm in a direction to move the valve into open position.

5. A spraying mechanism comprising, in combination, a pair of substantially parallel sills, upstanding supporting frames secured to said sills, each of said frames being substantially in the form of an inverted U, a saddle bridging the space between the upper portions of the side members of each of the frames, means for connecting the saddles to the side members, a tank resting on the saddles, means for holding the tank to the saddles, a spraying element in communication with the tank, a nozzle in communication with the tank, a valve for controlling the flow through the nozzle, an outstanding bracket carried by a saddle, a rocking arm pivotally engaged with said bracket and operatively engaged with the valve for moving the valve, means operable under weight connected with each rock arm for swinging the rock arm in a direction to move the valve into open position, and means for normally maintaining the valve in closed position.

In testimony whereof I hereunto affix my signature.

ANDREW McPHERSON.
